Primary Examiner — Calvin E Vansant*Assistant Examiner* — Mark T. Philippss(57) **CLAIM**

The ornamental design for an electric air pump, as shown and described.

DESCRIPTION

The patent or application file contains at least one drawing executed in color. Copies of this patent or patent application publication with color drawing(s) will be provided by the Office upon request and payment of the necessary fee.

1. Electric air pump

1.1 is a front view.

1.2 is a rear view.

1.3 is a left view.

1.4 is a right view.

1.5 is a top plan view.

1.6 is a bottom plan view.

1.7 is a front left top perspective view.

1 Claim, 7 Drawing Sheets**(7 of 7 Drawing Sheet(s) Filed in Color)**(56)
